AUGUST F. REICHERT AND JOSEF PICHLER, OF MILWAUKEE, WISCONSIN.

MACHINE FOR BENDING FLANGED BARS.

1,287,750.

Specification of Letters Patent. Patented Dec. 17, 1918.

Application filed February 14, 1916. Serial No. 78,185.

To all whom it may concern:

Be it known that we, AUGUST F. REICHERT and JOSEF PICHLER, citizens of the United States, residing at Milwaukee, county of Milwaukee, and State of Wisconsin, have invented new and useful Improvements in Machines for Bending Flanged Bars, of which the following is a specification.

Our invention relates to improvements in machines for bending flanged bars.

The object of our invention is to provide a simple, durable and efficient machine for bending flanged bars of different sizes; also to provide means whereby the bars may be subjected to rebending operations in the same machine; also to provide means whereby a flanged bar of any desired length may be bent circularly to form a ring or set of rings of the desired diameter, the bending operation being continuously performed regardless of the number of rings to be produced from the bar.

A further object of our invention is to provide a form of machine which may be easily and quickly adjusted to overcome distortion, to vary the degree of curvature or to accommodate bars which differ in size and thickness.

In the drawings—

Figure 1 is a plan view of a bending machine for flanged bars embodying our invention.

Fig. 2 is a front elevation of the same with a portion of the frame partially broken away to show the actuating mechanism.

Fig. 3 is a view of the table top as seen from the under side, showing the actuating mechanism.

Fig. 4 is a longitudinal sectional view of one of the adjustable rollers for applying vertical pressure to the flanged bar during the bending operation.

Fig. 5 is a detail sectional view of the adjustable bending roller, drawn on line $\alpha-\alpha$ of Fig. 2.

Fig. 6 is a similar view of the adjustable compression roller.

Like parts are identified by the same reference characters throughout the several views.

A table 1 is mounted upon a supporting bed frame 2 and is provided with a notch 3 in its front and top margin, the walls of which serve as a guide for the bars which, for convenience in description, may be assumed to comprise commercial angle iron bars or strips, one of which is indicated by

dotted lines α in Fig. 1. The bars α are fed through the notch 3, the base of which preferably has an upward inclination from the margin of the table inwardly. The bars are held down upon the table by an adjustable roller 5 adapted to bear upon the upper margin of the vertical flange. After passing underneath the roller 5, the advancing end of the bar passes over an anti-friction idle roller 7 and its vertical flange then passes between the peripheries of a set of compression rollers 9 and 10. The compression roller 9 is positively driven, as hereinafter explained, and serves to feed the stock, (the flanged bar to be bent), rearwardly after its vertical flange has been engaged between the compression rollers 9 and 10, its horizontal flange being also engaged either between roller 9 and roller 7, or between the roller 10 and roller 7. The roller 10 is an idle roller. Its vertical shaft 13 is mounted in supporting bearings 14 which slide in a suitable guide way 15 formed in the table top. The bearings 14 are pushed inwardly by means of an adjusting screw 17. A spring 18 is interposed between the inner end of the adjusting screw and the bearing member 14, the spring being provided with a cap 19 against which the adjusting screw 17 directly bears. The screw 17 has threaded engagement with the table and is manually actuated by means of a handle 20.

Between the compression roller 10 and the roller 5, an idle guide roller 25 is mounted upon a vertical axis, this roller being preferably located in a socket 26 formed in the table top, whereby the lower surface of this roller is brought more nearly on a level with the inclined base of the notch 3 along which the stock is fed. This roller 25 is so arranged that its periphery will bear against the stock and relieve the friction which would otherwise be exerted against the vertical wall at the right hand side of the notch 3, after the bending operation commences, the wall of said notch 3 and said roller 25 serving to prevent the in-feeding portion of the stock from swerving to the right when the other end portion of the bar is being bent to the left, as hereinafter explained.

The bending operation is performed by means of a bending roller 27 which acts in direct coöperation with the compression rollers 9 and 10. Assuming that an angle iron bar is being fed between the compres-

sion rollers 9 and 10, as shown by dotted lines in Fig. 1, it is obvious that when such a bar strikes the bending roller 27, it will be deflected to the left, owing to the fact that the bending roller occupies a position with its peripheral portion on the left hand side of the line along which the bar travels through notch 3 to the compression rollers. The axis of bending roller 27 is to the right 10 of said line and therefore the stock will be deflected to the left and caused to pass over the diagonal roller 30 which is also an idle roller adapted to revolve upon a horizontal axis. The shaft 29 of the bending roller 27 is journaled in a forked bearing member 33, adapted to slide in a suitable guide way 34 formed in the top of the table. It is adjusted along said guide way by means of an 15 adjusting screw 35, and when in the desired position of adjustment, is rigidly secured in such a position by means of a bolt 36 which passes through a slot 37 formed in the bottom of the guide way 34. The degree 20 of curvature imparted to the stock may therefore be varied by loosening the bolt 36 and retracting or advancing the adjusting 25 screw 35.

The function of the diagonal roller 30 is not only to relieve friction of the stock 30 upon the top of the table, but to correct distortion. Owing to the fact that the stock has a horizontal flange as well as a vertical flange, it is necessary to stretch the vertical flange and compress the horizontal flange 35 when the latter is passed under the compression roller 9. The stretching operation is largely performed by the pull exerted by the periphery of roller 9 upon the vertical flange to draw it between the base of the notch 3 and the initial guide roller 5. The rear end of the bar during this operation tends to bend downwardly, but is prevented from doing so by the roller 30, which is located at a sufficient distance from the compression rollers 9 and 10 to easily counteract the downwardly bending tendency. Further, the rollers 5 and 30 are each mounted upon supporting stationary shafts 40 and 41 respectively, and said shafts are eccentric 40 within the roller 5 (or 30), as shown at 42 in Fig. 4. This view shows the shaft 41, but it will be understood that shaft 40 is similarly constructed. These shafts are normally stationary but are provided with manually operated handles 45 and 44 respectively, whereby they may be adjustably rotated or oscillated upon their axes. When these shafts 40 and 41 have been thus adjusted to the desired position, they may be 45 locked in such position by any suitable means, such, for example, as the set screw 47. In each case, the roller 5, or 30, rotates upon the eccentric portion of the shaft, and by adjusting the shaft, the roller supported 50 thereon may be raised or lowered. The

movement is slight in proportion to the movement of the handles 44 and 45, and therefore these rollers may be very accurately adjusted, and the means for doing so is simple, substantial and reliable under the 70 heavy pressures exerted by the bars.

Shaft 40 which carries the feed controlling roller 5, is mounted in a sleeve bearing member 50 supported by a vertical post 51, which extends through a hole in the table 75 and through a tubular boss 52 depending from the table top. The bearing sleeve 50 may be raised or lowered and it also may be 80 rotatively adjusted about the axis of the post 51. To facilitate raising and lowering the post 51 and sleeve 50, we provide the sleeve with a bracket 55 having a segmental slot 56 therein through which an adjusting screw 57 passes, the lower end of the screw having threaded engagement in a socket or 85 hole formed in the table top underneath bracket 55. The adjusting screw or bolt 57 is provided with a head, and a washer is interposed between this bolt head and the bracket. The portion of the bolt which 90 passes through the slot 56 is reduced in size, the larger portion of the bolt below the bracket forming a shoulder upon which the bracket rests. Therefore, by rotating the bolt in its threaded bearings in the table top, 95 it may be raised or lowered and will carry with it the bracket 55 and sleeve 50. The sleeve 50 is held in any desired position of 100 rotative adjustment by a set screw 60, which has threaded bearing in the table top and which enters a hole in the boss 52 and is provided with a shoe 61 therein adapted to be pushed by the screw 60 into clamping engagement with the post 51. The screw 60 will of course be adjusted to release the shoe 105 from such clamping engagement whenever the sleeve 50 is to be adjusted, either rotatively or vertically. The rotative adjustment may be accomplished by simply taking 110 hold of the sleeve and swinging it to bring the roller 5 to the desired position, while the vertical adjustment is accomplished, as above explained, by means of the bolt or screw 57 in swiveling engagement with bracket 55.

Power is applied to the compression roller 9 through a pulley 70, clutch 71, shaft 72, worm 73 thereon, (Fig. 3), worm wheel 74, pinion 75 and gear wheel 76, the latter being fixed to vertical shaft 77 which carries 120 compression roller 9. The periphery of roller 9 is corrugated or milled to enable it to grip the vertical flange of the angle bar between it and roller 10. The teeth or ribs of these corrugations may be sufficiently 125 sharp to enter the vertical flange under the heavy pressure exerted thereon and thus feed the stock rearwardly with sufficient force to bend it when it comes in contact with the bending roller 27. A lever 80 is 130

employed to operate the main clutch 71, whereby the movement of roller 9 may be accurately controlled.

Briefly reviewing the operation and assuming that the angle bar is to be bent in the direction of the horizontal flange, the feed controlling or initial roller 5 will first be adjusted to its proper position over the notched or inclined way 3, so that it will bear upon the upper margin of the vertical flange when the angle bar is fed inwardly through said notch. Roller 5 may be raised by adjusting its cam shaft 40 so that the bar may be initially pushed underneath the roller 5 and over the roller 7 to a point where its vertical flange is brought in contact with the rollers 9 and 10, the horizontal flange passing under the roller 9. The machine may then be started, whereupon lever 44 will be swung to force the roller 5 into pressure contact with the upper margin of the vertical flange of the stock as soon as the end of said flange has been engaged between the compression rollers. The roller 9 will then operate to draw the stock, *i. e.*, the angle bar over the roller 7 and between the rollers 9 and 10, but since the flat under surfaces of rollers 9 and 10 occupy horizontal positions, whereas the stock is fed inwardly along the incline provided by the recess or notch 3, it is obvious that the stock will be bent into a substantially horizontal position while passing over roller 7. This operation stretches the metal in the vertical flange. As soon as the advancing end of the stock comes in contact with the roller 27, it will be deflected to the left. The vertical flange will of course bend in substantial conformity with the periphery of the roller 9 immediately beyond the point where such roller approaches most nearly to roller 10. The horizontal flange will be compressed by this bending operation, the greatest compression taking place along its margin. Roller 9, however, will be located so closely to the table top as to prevent this flange from buckling. The compression therefore results in merely thickening this flange or widening it horizontally, and also densifying the material appreciably where the grade of material used will permit.

Owing to the fact that the inclined base of the notch or recess 3 leads to an apex formed by the roller 7 over which the stock is being continuously bent toward the horizontal position while being fed between the compression roller, the rear end of the stock will tend to bend downwardly. This tendency, however, will be overcome, not only by the table top, but by the roller 30 over which the stock passes after its advancing end has reached this roller. The roller 30, by lifting the rear end of the stock, causes the stock to become bridged across the space between the rollers 7 and 30 and the under surface of

the compression roller 9 thereupon becomes more effective to prevent the horizontal flange from buckling along its inner margin, by reason the heavy pressure exerted upon its upper surface by the roller 9. 70 Where the stock is of sufficient length, a complete ring may be formed, or if desired, the operation may be continuous with stock of sufficient length to form a series of rings. In such case, the stock will be bent in the 75 form of a helix, the end initially passed between the compression rollers describing a complete circle and passing over the rollers in making the second turn. To vary the curvature, roller 27 will be adjusted inwardly or outwardly, as above explained. The adjustment of roller 10 will be made simply to vary the pressure.

It will be observed that the notch 3 has a curved left hand wall leading inwardly 85 in the table top along a curved line which converges toward the straight right hand wall. This form of the notch is desirable, for the reason that curved bars may be fed into the machine at times in order to change 90 their curvature, and when this is done, the curved form of the left hand side of the notch permits these bars to be fed inwardly along the incline with the same facility that the straight bars may be fed. We attach 95 great importance to the provision of means for feeding these angle bars inwardly to the compression rollers along an incline and bending them over an apex, such as is formed by the roller 7, since by so doing we 100 are able to stretch the metal in the angle formed by the two flanges sufficiently to permit the bending operation without buckling. We are enabled in the operation 105 of our machine to bend straight angle iron bars into circular form, producing rings of comparatively small diameter, with substantially smooth surfaced or unbuckled horizontal and vertical flanges. We are also able to prevent the flanges from deflecting from their respective horizontal and 110 vertical positions, whereas in other bending machines, so far as we are aware, great difficulty has been experienced in preventing the flanges from assuming inclined or distorted positions and in preventing them from buckling, the latter difficulty being principally experienced in the horizontal flange.

Our machine is equally adapted for bending angle bars into circular form with the horizontal flange outer-most. Where this is done, the horizontal flange passes underneath the rollers 25, 10 and 27. The vertical flange passes between the compression rollers 9 and 10 in the same manner, as above described. The three rollers 25, 10 and 27 prevent the horizontal flange from warping or twisting upwardly and the stretching 125 operation takes place principally at the 130

bending point immediately back of the point of nearest approach of rollers 9 and 10. In this operation also, the passing of the stock over the apex formed by the roller 7, greatly facilitates the operation of stretching the bar without permitting the flanges to twist or warp out of place.

We claim—

1. A bending machine for angle bars, including the combination with a table, of a set of compression rollers mounted thereon and adapted for pressure engagement of one bar flange between them, said rollers being located in sufficiently close proximity to the table to receive another flange between either of them and the table, an adjustable bending roller located in the rear of said compression rollers in the path of bars passing between such rollers, an adjustable guide roller adapted to hold the bars to be bent upon the table in front of the compression rollers, and an intermediate idle roller between the guide roller and the compression rollers over which said bars may pass, the upper surface of the table being inclined between said idle roller and the guide roller, together with a horizontally revoluble idle roller adapted to hold said bars against lateral swinging movements during the bending operations performed on the opposite side of the compression rollers by said bending roller.

2. A bending machine including the combination with a table having an inclined top surface and a horizontal top surface, of a set of compression rollers revoluble upon vertical axes above the horizontal surface and adjacent to the inner end of the inclined surface, a bending roller located in the path of the bars passing between the compression rollers and an initial guide roller adapted to hold the bars down upon said inclined surface while they are being drawn over the same by the compression rollers and progressively bent by said bending roller, together with a rear guide roller adapted to revolve upon a horizontal axis in the path of the bars passing the bending roller, whereby said bars may be lifted above the surface of the table between the compression rollers and said rear guide roller to facilitate the shaping operations.

3. A bending machine including the combination with a table having an inclined top surface and a horizontal top surface, of a set of compression rollers revoluble upon vertical axes above the horizontal surface and adjacent to the inner end of the inclined surface, a bending roller located in the path of the bars passing between the compression rollers and an initial guide roller adapted to hold the bars down upon said inclined surface while they are being drawn over the same by the compression rollers and pro-

gressively bent by said bending roller, together with a rear guide roller adapted to 65 revolve upon a horizontal axis in the path of the bars passing the bending roller, whereby said bars may be lifted above the surface of the table between the compression rollers and said rear guide roller to facilitate the 70 shaping operations, said rear guide roller being vertically adjustable to vary the degree of the lifting operation in correspondence with the requirements of the material.

4. A bending machine for angle bars, 75 comprising the combination with a supporting table, of compression rollers, means for actuating one of said rollers to feed angle bars between them, said rollers being arranged to receive the vertical flange between 80 their peripheries and the horizontal flange between their under surfaces and said table top, a bending roller having a peripheral portion in the path of bars which pass between the compression rollers, and adjustable means for applying an upward pressure to said bars in the rear of the bending roller, whereby they may be lifted from the table top in the rear of the compression rollers, together with means for depressing said 90 bars on the feeding-in side of the compression rollers below the plane of the table top.

5. A bending machine for angle bars, comprising the combination with a table, of an actuating roller mounted to revolve horizontally 95 above the surface of the table and having gripping teeth on its periphery adapted to engage one flange of the bar, a co-operative compression roller having its periphery in close proximity to said gripping teeth, 100 means for permitting said rollers to separate, means for resiliently opposing separating movements thereof, said rollers being adapted to receive the vertical flanges of angle bars between their peripheries and to 105 also receive horizontal flanges between their under surfaces and said table top, means for guiding angle bars between said rollers, and means for progressively and continuously bending such bars in one direction in the 110 angle formed by the diverging peripheries of said rollers as the bars move between them, said bars being forced rearwardly between said rollers by the gripping action of said teeth and by the frictional contact 115 of the rollers upon the bar surfaces, together with means for bending said bars downwardly on the in-feeding side and upwardly on the out-feeding side of said rollers.

In testimony whereof we affix our signatures in the presence of two witnesses.
